PATIO COVER PANEL PAN

Arthur E. Haskell, Downey, William N. Brummet, Burbank, and Robert Fitzgerald, Huntington Beach, Calif., assignors to State Industries, Huntington Park, Calif.

Filed Mar. 13, 1970, Ser. No. 21,893

Term of patent 14 years

Int. Cl. D25—01

U.S. Cl. D54—2

FIG. 1.

FIG. 2.

FIG. 3.

FIG. 1 is a perspective view of a patio cover panel pan showing our new design;

FIG. 2 is an end view of the panel pan illustrated in FIG. 1; and

FIG. 3 is an end view of another embodiment of our new design wherein the horizontal portions and the articulated upwardly and outwardly extending portions may vary in length without departing from the scope of our design.

We claim:

The ornamental design for a patio cover panel pan, substantially as shown and described.
